(57) **CLAIM**

The ornamental design for a media player device, as shown and described.

DESCRIPTION

FIG. 1 is a top plan view of a media player device, showing our new design.

FIG. 2 is a partially enlarged view thereof, taken from FIG. 1.

FIG. 3 is front elevation view thereof.

FIG. 4 is a rear elevation view thereof.

FIG. 5 is a bottom plan view thereof.

FIG. 6 is a first side view thereof.

FIG. 7 is a second side view thereof.

FIG. 8 is a top perspective view thereof; and,

FIG. 9 is a bottom perspective view thereof.

The broken lines in the figures illustrate the portions of the media player device that form no part of the claimed design. The dot-dash broken lines of FIGS. 1 and 2 are included to show partially enlarged views only and form no part of the claimed design. The dot-dot-dash broken lines are included to show boundaries of surfaces of the claimed design. The evenly-spaced dotted lines on the top in FIGS. 1, 2, 8 and evenly-spaced dashed broken lines shown across the surfaces in FIGS. 3-5, 9 are included to show unclaimed seam lines and form no part of the claimed design.
